RECTIFIER

Henri G. André, Suresnes, France

Application August 24, 1929, Serial No. 388,181.
Renewed August 22, 1934. In France October
5, 1928

13 Claims. (Cl. 175—366)

This invention refers to an electrochemical rectifier of current, with solid electrodes in contact, characterized by the automatic regeneration of the surfaces in contact.

It has been pointed out, as a matter of fact, that all the devices of this kind are very short lived, are unreliable in their operation, and are destroyed even at rest, due to the decomposition or the combination of the substances facing each other which react between themselves or with the elements of the ambient air.

This is the case in particular of the rectifiers provided with metal oxides and metal sulfides, the operation of which is satisfactory but momentarily.

Indeed, all these types are the seat of numerous microscopic sparks which heating locally the particles of the substances in contact, bring about in the presence of steam a reduction of the oxide or of the sulfide used and thereupon a subsequent bad rectification.

This decomposition may be made slower by the drying of the ambient air or by the limitation of the water vapor contents of the air as suggested hereinafter, but this necessary safeguard is insufficient because the dampness absorbed by the products in contact may in turn exercise an injurious action.

For the condition of the substances in contact not to undergo any change, it is necessary to resort to a chemical agent which under the influence of the sparks keeps the composition of the electrodes unchanged.

For instance, if there is used as anode sulfide of copper or silver or of other electro-positive metal, as specified, for example, in the patent to Lilienfeld, No. 1,611,653, it will be necessary to place close to the sulfide a product capable of resulfurizing in a proper manner, the contact surface. The use of sulfur would appear practicable at first glance, but its low melting point makes it unsuitable because it would soon isolate the electrodes from each other. On the other hand, it is necessary that the insulating film of metal oxide on the cathode be kept up in a uniform and continuous manner. This invention makes use of concentrated sulfuric acid which offers a thorough solution of the problem in all cases where sulfides are resorted to.

In this invention instead of a sulfide I have discovered that a metal phosphide may be used for the anode in which case phosphoric acid is used to accomplish the desired results specified above.

It is likewise essential that the products in

contact be as intimate a contact as possible. When they are coated with their final chemical composition they are not very malleable, and a heavy pressure which would be permissible in the case of one or two soft electrodes is invariably injurious to the good preservation of the contact.

This invention also bears on the securing on the spot of the final chemical state of the electrodes in contact with a maximum of contact points.

Particularly in the case of silver sulfide, a rather brittle product under certain conditions, the invention makes provision for the shrouding of the cathode by means of a silver element which upon its being sulfurated, allows through its porosity, of the conveyance of the regenerating product. The anode will therefore be constituted preferably by a thin perforated plate or even better, by a silver wire wound around the cathode. It will thereupon be transformed superficially into a sulfide or subsulfide through emersion in a melted sulfur bath and through heating by a higher temperature. This treatment shall be renewed a number of times which will be the greater the thicker the coat of sulfuration sought to be obtained; the best thickness will be determined by a compromise between the inverse tension that is to be borne by the rectifier and the minimum Joule loss.

My invention will be best understood from the following description of an exemplification thereof, reference being had to the accompanying drawing, in which

Fig. 1 is a view of the rectifying element;

Fig. 1a is an enlarged cross-sectional view of a portion of the element shown in Fig. 1;

Fig. 2 shows a different form of rectifying element;

Fig. 3 illustrates an arrangement for leading the current into the rectifying element;

Fig. 4 shows my rectifying element enclosed in a sealed envelope;

Figs. 5 and 6 show two arrangements for mounting my rectifying element in the container;

Fig. 7 shows an arrangement for supplying a reserve of regenerating liquid to my novel rectifying element;

Fig. 8 illustrates an arrangement for sealing the rectifying element within a container; and

Fig. 9 shows another arrangement for supporting the assembly shown in Fig. 8 within an outer vented container.

The cathode of my novel rectifying device preferably consists of an oxidizable metal, such as

silicon or an alloy thereof. Of course it will be understood that any of the other oxidizable metals which are commonly used in the type of rectifier with which I am dealing, may also be used as the cathode as described, for example, in the patent to Lilienfeld, No. 1,611,653, and the patent to Pawlowski, No. 830,924. For the anode I utilize either a metallic sulphide, such as silver, or copper sulphide or phosphide, such as silver or copper phosphide. The anode and cathode are placed in intimate contact with each other, the cathode in its operating condition having formed thereon a layer of its oxide. As pointed out above, my invention contemplates the use of a regenerating material for maintaining the surfaces of both the anode and the cathode. In the case where sulphides are used, this material consists of concentrated sulphuric acid which is placed in immediate vicinity of the contact between the cathode and anode. In the case of phosphides, this material consists of phosphoric acid.

Fig. 1 shows the rectifying element referred to above by way of example. It shows cathode 2, on which is wound anode 1 consisting of a silver wire. The enlarged cross-section in Fig. 1a shows sulfuration coat 3 forming after the sulfuration and the oxidation coat 4, brought about by the action of the regenerating sulfuric acid with which the coils have been impregnated after sulfuration.

In the special cases of sulfide of silver, cathode 2, (Fig. 2) may be coated, due to the porosity of this compound, with these melted substances, there being thereby secured the coating 3'. Thereupon the current may be led in either (Fig. 2) by a wound silver wire or (Fig. 3) by a metal powder 6, which has the advantage of keeping up a reserve of regenerating liquid. This powder would not exercise any so-called valvular effect either on the sulfide of silver or on the metal wall through which the current is brought in, and for this purpose it will itself consist of silver as the metal wall itself.

Fig. 3 shows the leading of the current into anode 3 of sulfide of silver through powder 6 which in turn receives this current from the inner wall of container 5.

As it has been pointed out at the outset, it is absolutely necessary to remove the rectifying element from contact with moist air. If the quantity of regenerating acid is small or if the product used does not give rise to any release of gas, it will be advisable to enclose quickly the element immediately after its manufacture in a glass bulb where a vacuum will be produced. There may be adopted with advantage an arrangement similar to the one adopted in the case of incandescent electric lamps.

Fig. 4 shows such an arrangement; the rectifying element 1-2 is set up on a glass foot 7 soldered to bulb 8 which may be closed without a previous formation of vacuum, or preferably with a previous formation of vacuum, it being still better to enclose an additional water absorbing medium having a greater absorption power than the acid or the regeneration used.

If the liquid used is partially electrolyzed and if the quantity utilized is large, there arises the risk of a dangerous increase of the pressure inside of the bulb. The substitution of metal for glass would merely delay the danger of an explosion.

Resort has therefore been had to a mechanical valve device which is one of the essential fea-

tures of the type of apparatus covered by this invention.

By measure of safeguard there is first of all effected a plugging by means of a plastic substance set on the outlet of a metal tube containing the electrodes. To make easy such shutting the electrodes are set up at the bottom of the tube either according to the arrangement shown in Fig. 5, or according to the arrangement shown in Fig. 6. In these two assemblies the cathodes are provided with a shoulder which rests on the bottom of the tube through the insertion of insulating mica washers 9. The metal washer 10 holds the cathode against the bottom of the tube. The washers are coated in advance with bakelite varnish or other substances absolutely water proof.

Fig. 7 shows the mechanical layout of Fig. 5, with a reserve 11 of regenerating liquid shut up in a neutral substance such as silica or of spun glass.

The electrodes being thereby fastened to the bottom of metal tube 5, there is established an upper plugging which is isolated by capillarity from the liquid reserve through a glass tube 12 (Fig. 8) resting on mica washers 13. Above the upper washer there is an asbestos stopper impregnated with bakelite varnish 14, which is almost tight. A coating of gas tar 15 or of any other plastic wax makes the sealing a thorough one.

This latter protection may prove sufficient if the release of gas is small; it insures the perfect keeping of the rectifier while in storage and not in operation but if while the rectifier is in service plastic material 15 is pushed down, it may happen that it does not come back to seal the tube, and in such a case provision is to be made for a device affording the possibility of draining the released gas and barring the way of an influx of water vapor.

This invention contemplates therefore in this connection an additional mechanical valve.

The arrangement of this mechanical valve is made difficult by the circumstance that in view of the danger of the gas inside exploding accidentally, it is necessary to avoid any compression of such gases and on the other hand, the sealing should be as good as possible to insure a proper keeping.

The inner pressure being intended to be small, the flap of the valve shall be made preferably of rubber or of any other similar substance.

The use of rubber bars, of course, does not allow the resort to any exaggerated high temperature. It is therefore necessary, upon the rectifier becoming somewhat heated, to isolate thermally the valve seal of the housing.

For this purpose the valve seal is made of a thermic insulating material such as cast bakelite.

Fig. 9 shows by way of example the arrangement of the complete elements of an electrochemical rectifier with automatic regeneration and of remarkable keeping qualities.

It shows the use of the rectifying element of Fig. 6, sealed according to the arrangement of Fig. 8. The rectifier is set up in a socket 16 (Fig. 9) Edison type, containing tar 17 which increases the seal while holding the apparatus; the connection of the latter is effected on the one hand with central contact 18, of the cap, and on the other hand with the mass of a sheath 19.

This tube is inserted by a casting process in plug 20 made of bakelite or other similar moulded material. The plug itself is arranged in such a manner as to receive in the upper hole a rubber disk 21 which seals the narrow passage 22, lead-

ing to the inside of the housing. The disk is pressed against hole 22 by a spring 23 adjusted by screw 24, held in a threading of the plug. Release canals which are not shown, may be driven radially in the plug between its outer surface and the housing of spring 23.

It is clear that the system of protection described above surmounted by its valve plug may contain any number of rectifiers for objects of economy, the connections between the elements being made inside the housing supporting the valve, further means of connections (clamps, terminals, etc.) being furthermore contemplated to make sure the connection of the apparatus with outside circuits.

I claim:

1. A rectifier comprising a cathode of oxidizable metal, an anode of a sulphide of an electro-positive metal in contact with said cathode, and concentrated sulphuric acid immediately adjacent the contacting surfaces of said cathode and anode.

2. A rectifier comprising a cathode having a layer of metallic oxide on its surface, an anode having a layer of a sulphide of an electro-positive metal on its surface, said cathode and anode surfaces being in contact with each other, and concentrated sulphuric acid supplied to said contacting surfaces.

3. A rectifier comprising a cathode of oxidizable metal, an anode in close proximity thereto, a sulphide of an electro-positive metal in contact with and connecting said cathode and anode, said sulphide being porous, and concentrated sulphuric acid provided through said sulphide.

4. The method of making a rectifier which comprises placing on the surface of an oxidizable metal, another electro-positive metal having a stronger affinity for sulphur than said first metal, said second-named metal being in close contact with the surface of said first-named metal, converting the surface of said second-named metal into its sulphide, supplying a concentrated sulphuric acid to the contacting surfaces of said metals, a coating of oxide being formed on the surface of said first-named metal at any time during the above-mentioned steps.

5. A rectifier comprising a cathode of oxidizable metal, an anode of a sulphide of an electro-positive metal in contact with said cathode, and a metallic powder in contact with said anode serving as a current lead thereto.

6. A rectifier comprising a cathode of oxidizable metal, an anode of a sulphide of an electro-positive metal in contact with said cathode, concentrated sulphuric acid supplied to the contacting surfaces of said cathode and anode, said rectifier being disposed in a container, and means

associated with said rectifier for venting the gases formed.

7. A rectifier comprising a cathode of oxidizable metal, an anode of a sulphide of an electro-positive metal in contact with said cathode, concentrated sulphuric acid supplied to the contacting surfaces of said cathode and anode, said rectifier being disposed in a container, and means associated with said rectifier for venting the gases formed, said venting means being thermally insulated from the rectifier itself.

8. A rectifier comprising a cathode of oxidizable metal, an anode of a sulphide of an electro-positive metal in contact with said cathode, concentrated sulphuric acid supplied to the contacting surfaces of said cathode and anode, said rectifier being disposed in a container, and means associated with said rectifier for venting the gases formed, said venting means comprising a one-way valve allowing escape of gases from the interior of said container but preventing entrance of fluids into said container.

9. A rectifier comprising a cathode of an oxidizable metal, an anode of silver sulphide in contact with said cathode, and a concentrated sulphuric acid immediately adjacent the contacting surfaces of said cathode and anode.

10. A rectifier comprising a cathode of an oxidizable metal, an anode of copper sulphide in contact with said cathode, and a concentrated sulphuric acid immediately adjacent the contacting surfaces of said cathode and anode.

11. A rectifier comprising a cathode having a metallic oxide on its surface, an anode having a sulphide of an electro-positive metal on its surface, said cathode and anode surfaces being in contact with each other, and a re-sulphurizing and re-oxidizing medium supplied to said contacting surfaces.

12. A rectifier comprising a cathode having a metallic oxide on its surface, an anode having a sulphide of an electro-positive metal on its surface, said cathode and anode surfaces being in contact with each other, and a sulphur and oxygen containing compound supplied to said contacting surfaces.

13. The method of making a rectifier which comprises placing on the surface of an oxidizable metal another electro-positive metal having a stronger affinity for sulphur than said first metal, said second-named metal being in close contact with the said first-named metal, converting the surface of said second-named metal into its sulphide, supplying a sulphurizing and oxidizing medium to the contacting surfaces of said metals, a coating of oxide being formed on the surface of said first-named metal at any time during the above-mentioned steps.

HENRI G. ANDRÉ.
